UNITED STATES PATENT OFFICE.

FEODOR GRAUL, OF LEIPZIG-SCHLEUSSICH, GERMANY.

MACHINE FOR PASTING PIECES OF GOODS ON SAMPLE-CARDS.

1,126,003.

Specification of Letters Patent.

Patented Jan. 26, 1915.

Application filed February 16, 1912. Serial No. 678,035.

To all whom it may concern:

Be it known that I, FEODOR GRAUL, a citizen of the Empire of Germany, and a resident of Leipzig-Schleussich, Kingdom of Saxony, Germany, have invented certain new and useful Improvements in Machines for Pasting Pieces of Goods on Sample Cards, of which the following is a specification.

30 This invention relates to a novel machine for pasting pieces of goods on sample cards. According to the present invention the machine shall be used for pasting pieces of goods, cloth and the like on sample cards 15 which comprises the usual means for placing the sample cards in position, and in addition thereto a pasting device and a device for cutting the samples of the goods. The pasting and the cutting devices are so arranged that the paste supplying means as well as the suction device, which lifts off the samples of the goods are placed above the sample cards to be operated on by means of a swing arm.

25 The invention is illustrated in the accompanying drawing in which;

Figure 1 represents in plan view the machine for pasting pieces of goods on sample cards which embodies in desirable form the 30 present improvements. Fig. 2 illustrates in elevation one form of the machine. Fig. 3 shows in elevation certain mechanism of same. Figs. 4 and 5 are plan views of the shifting devices for mechanism shown in 35 Fig. 3. Figs. 6, 6^a and 7 are plan views of certain modifications. Fig. 8 illustrates on an enlarged scale in partial sectional elevation a reciprocating card conveyer with 40 grippers. Figs. 9 and 10 show the gripper arrangement in end views on an enlarged scale.

Similar characters of reference denote like parts in all the figures.

In the machine illustrated there is a central table 1 upon which is mounted an automatic device for lifting off the sample cards. This device is so constructed that the lowest card is always taken away first and transported step by step to the glue supplying 45 means and pasting station and by means of the same movement it is led to the device for pressing on the pieces of cloth, etc. which device delivers the pasted and pressed sample cards to a roller 43. The removal of single cards from below presents the great advantage that the pile of cards may be

replenished without stopping the machine whereby the efficiency of the same is greatly increased.

In the device illustrated a carriage or card 60 conveyer 3 shown in Fig. 2 is reciprocated by means of a crank mechanism 2, shown in Fig. 1. This conveyer carries elastic grippers 4. These grippers seize when moving toward the pile of cards always the lowest 65 card and push it in the desired position. On their backward movement these grippers shift underneath the card and return into their initial position whereupon the described operation is repeated. As there are 70 several grippers of the described kind a card will be taken from underneath the pile during the next operation, and the card previously removed therefrom will be guided to the glue supplying device and pasting station. During the next operation this is repeated and the pasted card is conducted to the device for pressing on the pieces of cloth. This latter device further transports 75 same automatically to the delivery station. 80

In order to render the construction and operation of the conveyer and gripper mechanism entirely clear, I will describe same now in detail. As hereinbefore stated the conveyer 3 is reciprocated by means of the 85 crank mechanism 2. Pairs of grippers 4^a-4^a, 4^b-4^b, and 4^c-4^c are provided on the conveyer 3 as shown in detail in Figs. 8, 9 and 10. Each of those grippers is under the slight tension of a spring F, which is 90 adapted to retain the gripper in its straight upward and vertical position. The gripper end then seizes a sample card from the rear to transport same. During the first movement of the conveyer the lower card is separated from the pile by the grippers 4^a and placed upon the middle of the conveyer as 95 shown in Figs. 1 and 8, its location being designated by I in Fig. 8. During the second movement of the conveyer the grippers 4^a remove a second card from the pile, also 100 from below. This card likewise is brought into the position I. Simultaneously the grippers 4^b place the first transported card on the end of the conveyer as shown at II in 105 Fig. 8. In the position II the pieces of cloth are brought to this card. During the third movement of the conveyer the grippers 4^a seize another card from the pile and bring it into the position I. At the same 110 time the grippers 4^b transport the card from the position I into the position II and the

grippers 4^e deliver the card with pieces of cloth thereon to the rollers 42.

All the grippers rock backward under the cards during the backward motion of the conveyor and slide below the cards as shown in Fig. 10. The elasticity of the springs F is so little that they permit of the backward rocking of the grippers under the cards, but the springs are strong enough to place the grippers in their initial vertical position as soon as they have passed the card.

In addition to the above described devices, a gluing device 5 shown in Fig. 1, a cutting mechanism 6 which cuts strips of goods suitably conducted thereto and a suction device 7, are arranged so that a swing arm 8 is capable of gluing the card now below same. A second swing arm 9 takes up the cut pieces of goods and guides same onto the card.

In the device illustrated in Figs. 2 and 3 the swing arms 8 and 9 are shown to be provided, the first with a number of glue supplying members 10 and the second with a number of suction devices 7. These members 10 and 7 are rotatable around a vertically mounted axle and may also be moved up and down. This up and downward movement of the axle is caused by a cam disk 12 on the main shaft 21. Above the cam disk there is a vertical axle 14 with reduced lower end portion. A roller 13 is rotatably mounted on said reduced lower end portion and adapted to contact with the cam disk 12 whereby the up and downward movement above mentioned is effected. The shaft 14 is guided in a sleeve 15. Another shaft 11 rests with its bottom end on the shaft 14 which is therefore forced to perform the up and downward movement of the same. The sleeve 15 is rotatably mounted with a shifting disk 16 which has two oppositely arranged slots 17 and forms four inwardly curved surface portions 18 which coöperate with the stop disks 19, 20 when after rotation the shifting disk shall be securely held in place as shown in detail in Figs. 4 and 5. The entire shifting motion is effected from the main shaft 21 which is connected to the driving shaft. On said main shaft there are, in addition to the cam disk 12 which effects the up and downward movement, two bevel-gears 22, 23 see Fig. 2. The bevel-gear 22 drives the bevel-gear 24 toward the left and the bevel-gear 23 the bevel gear 25 toward the right shown in Fig. 3. The bevel-gears 24, 25 are connected with two shift levers 28, 29 by means of the bolts 26, 27. The shift levers 28, 29 carry each on the front portion a roller 30 which reaches into the slots 17, 17 of the shifting disk 16 and moves same thereby. As shown in the drawing the roller 30 reaches into the slots 17 of the shifting disk 16 and turns same in the direction of the arrow 31 for

exactly 90° and when in this position the roller 30 leaves the slot again. In this manner the slot 17 has been turned for 90° as well as the roller 30 which latter is now together with the shifting disk 16 in the position shown in Fig. 5. Now the mechanism is at rest for a moment during which time the stop disks 19 locate themselves in the inwardly curved portions 18 of the shifting disk 16 whereby this mechanism is securely held. During this short period of rest the up or downward movement of the axle 14 takes place for the purpose of gluing the cards and bringing the pieces of goods upon same. During the following further motion the stop disk 19 leaves the inwardly curved portions 18, the roller 30 reaches into the slot 17 whereby the shifting disk 16 has returned to its initial position. After this movement there is again a short period of rest during which time the stop disks 20 enter the curved surface portions 18 and hold securely the shifting disk. The axle 14 is secured against rotation by means of a cam disk 32 in slot 33 of the permanently fixed wheel box 34. The axle 11 however is taken along by a cam disk 35 which is located in the slot 36 of the sleeve 15. This shifting mechanism is arranged as well for the swing arm 9 as for the swing arm 8 as shown in Fig. 2. Both movements may be so adjusted that, after the card has been glued by the glue supplying members 10 and the latter are on their return way, the swing arm 9 presses the samples of cloth upon the glued spots. The swing arm 9 further is so constructed as to form a suction conduit therefore it is connected with a rarefied space or an air pump 38 by means of a hose 37, as shown in Fig. 1. On the front end of said suction conduit there are suction mouth pieces 7 which are adapted to be set upon the cut off pieces of cloth. By means of the suction these pieces are attracted and held during the swinging motion of the arm 9 and finally they are placed upon the glued portions of the cards and pressed thereon. The mechanism illustrated in elevation in Fig. 2 further shows how the glue roller 5 may be driven by means of bevel-gears and cord, chain or belt devices. The operation of the device for pressing on the pieces of cloth may be effected in similar manner while the operation of the cutting mechanism is effected by means of the drawing-rod 39.

According to the form of the machine illustrated the operation of same is substantially as follows: The cards are singly removed from underneath and gradually brought into the desired position 40 as shown in Fig. 1. During this phase of the operation the swing arm 8, Fig. 2, is set into motion, the glue supplying members 10 pass over the glue roller 5 and take off some of

the glue thereon. The glue supplying members then move further until they are above the card, whereupon they descend and deposit the glue on this card. Now the arm 8 ascends together with the glue supplying members 10 and returns into its initial position. During these operations strips of goods 41 have been automatically moved forward a determined length and are cut off by the cutting device. The cut pieces are taken up by the suction device and during the return of same taken above the glued card by means of the swing arm 9. When in this position said swing arm 9 descends with the suction mouth pieces 7, which press the sample pieces upon the glued spots, are raised again and return into their initial position whereupon the cycle of operations is repeated. During the next operation the card now covered with the sample pieces glued thereon is conducted to a system of rollers 42. These rollers press the sample pieces again tightly onto the cards and transport the finished cards automatically through the roller 43 out of the machine.

It is evident that the detailed construction of the single mechanisms above mentioned is not of importance for the present invention. The arrangements of the swing arm may also be changed for instance, so that two, three or more sets of sample pieces may be pasted upon a card as shown in Fig. 6. Assuming that two sets of sample pieces are to be placed upon one card then the glue supplying members 10 on the swing arm 8 are so constructed that two rows of glued spots are produced on the card. After this has been effected by a turning movement of the swing arm 8 then the swing arm returns into its initial position and the two swing arms 9 are brought upon the card as indicated by the elongated curved arrows, shown in Fig. 6. In this manner two sets or rows of sample pieces are placed upon the one card. This arrangement is shown in Fig. 6 while at rest. Fig. 6a shows in detail view the part 10 with two pasting faces thereon. The motion of the swing arms 9 is effected by means of the two tooth wheels 44, 45.

The double arrangement of the machine may be effected by providing two automatic card-passes, a double swing arm for the gluing device which in turn is then provided at each side with a corresponding cutting and suction device as indicated in Fig. 7.

I claim as my invention:

1. A machine for pasting pieces of goods on sample cards comprising an automatic card pass, a gluing roller, glue supplying members, a swing arm actuating same, a sample piece cutting device, and a swing arm having suction mouth pieces adapted to transport the cut pieces to the glued spots of the card.

2. Machine for pasting pieces of goods

on sample cards comprising an automatic card pass, a gluing roller, a swing arm with glue supplying members so arranged that it contacts with the glue roller when moving forward to take off glue and deposit same upon the card and is raised above said glue roller when returning into its initial position, means for cutting samples of goods and means for transporting the same to the glued spots of the cards.

3. In a machine for pasting pieces of goods on sample cards comprising automatic card passes, a glue roller, glue supplying members, a double swing arm for actuating same, suction mouth pieces, and a swing arm for actuating same on each card pass.

4. In a machine for pasting pieces of goods on sample cards, a working table, a pile of cards thereon, means for transporting same step by step to the desired place, comprising a card conveyer below the table having a series of grippers mounted so that they are adapted to make a to and fro motion, a gluing roller, glue supplying members, means for cutting samples of goods and means for transporting the same onto the glued spots of the cards.

5. In a machine for pasting pieces of goods on sample cards, means for supporting the pile of cards, a card conveyer below same having a series of grippers adapted to perform a to and fro motion and so arranged that during their forward movement the lowest card is removed and transported from station to station and upon their return may be pressed down by the card, a gluing roller, glue supplying members, means for cutting samples of goods and means for transporting the same onto the glued spots of the cards.

6. In a machine for pasting pieces of goods on sample cards, a shaft, a swing arm on said shaft, glue supplying members on said swing arm, a sample cutting device, a second swing arm on a second shaft, suction mouth pieces on the second swing arm for transporting the cut samples, and shifting mechanism so arranged that the glue supplying members are first shifted and then the suction mouth pieces to transport the cut samples.

7. In a machine of the type described, an automatic card pass, a gluing roller, a swing arm with glue supplying members thereon, said glue supplying members being so arranged as to supply glue to the card in various spots side by side and behind each other, means for cutting samples of goods, and means for transporting the same to the glued spots on the cards.

8. In a machine of the type described, an automatic card pass, means for supplying glue to the cards on various spots side by side and behind each other, a sample piece cutting device and a swing arm having suc-

tion mouth pieces so arranged that the same are adapted to transport a multiple of sample pieces and deposit same side by side and behind each other in the glued spots of the cards, means for pressing said samples thereon, and means for transporting the finished cards out of the machine.

9. In a machine of the type described, an automatic card conveyer, a swing arm with 10 glue supplying devices, a second swing arm adapted to transport cut sample pieces of cloth, and means for moving the swing arms in their end positions and securing them periodically therein comprising a shifting

disk having oppositely arranged slots and 15 inwardly curved surface portions, a shaft with a shifting lever at each side of the disk adapted to enter a slot of the latter, and a shifting arm on each of said shafts adapted to engage the inwardly curved surface portions of the shifting disk.

Signed at Leipzig, Germany, this 2d day of January 1912.

FEODOR GRAUL.
